UNITED STATES PATENT OFFICE.

ERNEST G. LEITH, OF TITUSVILLE, PENNSYLVANIA.

CHIMNEY AND CHIMNEY-FLUE.

No. 893,528.

Specification of Letters Patent.

Patented July 14, 1908.

Application filed June 8, 1907. Serial No. 378,007.

To all whom it may concern:

Be it known that I, ERNEST G. LEITH, a citizen of the United States, residing at No. 57 Breed street, in the city of Titusville, in 5 the county of Crawford, in the State of Pennsylvania, have invented new and useful improvements in chimneys and chimney-flues for use in dwelling-houses or other buildings, whereby the same can be built practically 10 fire, water, and weather proof.

This invention relates to chimneys for dwelling houses, factories and other buildings and has for its object to provide a chimney which is strong and durable in construction 15 and which will effectually withstand the action of the elements for an indefinite period.

A further object is to provide a chimney the base of which is formed with a reduced extension which projects through the roof of 20 the building for connection with the chimney flue, there being a laterally extending shoulder formed on the base of the chimney at the reduced portion thereof and having its lower longitudinal edge inclined to conform 25 to and adapted to bear against the upper surface of the roof.

A further object is to so position the base of the chimney on the roof of the building that said base will extend between and be 30 supported by the adjacent rafters with the ends of the sheathing boards and roofing material projecting beneath the shoulder thereby to form a water, fire and weather proof joint where the chimney projects through the roof 35 of the building.

A still further object of the invention is to generally improve this class of devices so as to increase their utility, durability and efficiency.

40 Further objects and advantages will appear in the following description, it being understood that various changes in form, proportions and minor details of construction may be resorted to within the scope of the 45 appended claims.

In the accompanying drawings forming a part of this specification: Figure 1 is a side elevation of a chimney base constructed in accordance with my invention showing the 50 same in connection with an ordinary brick chimney. Fig. 2 is a similar view showing the base used in connection with a chimney formed of cement blocks. Fig. 3 is a side elevation of the chimney base detached. Fig. 4

is an end view of the same. Fig. 5 is a top 55 plan view of two of the blocks forming the chimney shown in Fig. 2, two of the blocks being also shown detached from said chimney.

Similar numerals of reference indicate corresponding parts in all of the figures of the 60 drawings.

The improved chimney base forming the subject matter of the present invention is shown in Fig. 1 of the drawings in connection with an ordinary brick chimney in which 65 A designates the base and F the cap which rests on the upper layer of bricks forming the chimney and serves to prevent the water from percolating downwardly through the bricks and mortar and eventually destroying 70 the same.

The chimney base A is preferably rectangular in shape, as shown and formed of cement, concrete and other suitable material, said base being provided with a reduced extension 75 E defining a laterally extending stop shoulder which entirely surrounds the side walls of the chimney base, as indicated at B and C in the several figures of the drawing.

The reduced extension E projects downwardly through an opening in the roof of the building between the rafters D for connection with the chimney flue, as shown, the side walls of the extension E being disposed flush with the exterior walls of the chimney 85 flue so as to present a smooth unobstructed surface.

The lower longitudinal edges of the stop shoulder on two sides of the base A are inclined upwardly towards the center of said 90 base to conform to the pitch or inclination of the roof and are designed to rest on the adjacent rafters D with the ends of the roofing boards and ridge boards (when said ridge boards are used), interposed between the 95 rafters and the inclined edges of the shoulder, as best shown in Figs. 1 and 2 of the drawing.

The remaining longitudinal edges of the shoulder are disposed parallel with the lower end of the extension E and rest against the 100 sheathing or roofing boards thus forming a water and fire proof joint where the chimney projects through the roof of the building while at the same time serving to prevent accidental displacement of the roofing boards. 105

Attention is here called to the fact that by interposing the base A between the adjacent rafters D the chimney base is locked against

accidental displacement while the rafters by indirect engagement with the stop shoulder serve to assist in sustaining the weight of the chimney base.

5 In Fig. 2 of the drawings the chimney proper is shown constructed of angularly disposed concrete blocks G arranged in superposed courses and arranged to break joint with the cap plates F bearing against the 10 upper course and with the reduced extension E of the chimney base engaging the chimney flue, as shown.

It will of course be understood that the extension E may be made in different lengths 15 according to the conditions under which it is used, while the lower edges of the stop shoulder may be inclined to correspond to the inclination of the roof of the building.

From the foregoing description it will be 20 seen that there is provided an extremely simple, inexpensive and efficient device admirably adapted for the attainment of the ends in view.

Having thus described the invention what is claimed is:

A chimney base including a hollow substantially rectangular body portion having its exterior walls partially cut away to produce a circumferential stop shoulder defining a reduced portion, the walls of which are disposed parallel with each other, the exterior walls of the body portion between the shoulder and the upper end thereof being solid and free from surface projections to form a reinforcement, two of the opposite longitudinal edges of the shoulder being under-cut and arranged parallel with the bottom of the body portion and the remaining longitudinal edges of said shoulder inclined upwardly from the corners of the body portion and intersecting on said body portion.

ERNEST G. LEITH.
